UNITED STATES PATENT OFFICE.

WILLIAM B. JACOBS, OF NEW YORK, N. Y.

DESIGN FOR A GLASS OR LIGHT.

SPECIFICATION forming part of Design No. 30,001, dated January 10, 1899.

Application filed December 17, 1898. Serial No. 699,606. Term of patent 14 years.

To all whom it may concern:

Be it known that I, WILLIAM B. JACOBS, of the borough of Brooklyn, New York city, in the State of New York, have invented and produced a certain new and original Design for a Glass or Light; and I do hereby declare that the following is a full, clear, and exact description thereof, reference being had to the accompanying drawings, in which—

10 Figure 1 is a perspective view of a glass or light embodying my design, and Fig. 2 a cross-section of the same.

Letters of like name and kind refer to like parts in each of the figures.

15 The object of my invention is to provide a design for a glass or light for illuminating gratings; and to this end said invention consists in the design for a glass or light, substantially as hereinafter set forth.

20 The leading feature of my design consists of parallel ribs on the glass or light, each of which has a triangular form in cross-section,

the sides of the triangle being respectively convex and concave, which ribs alternate with other ribs that are smaller and are triangular in cross-section. 25

The glass is in the form of a rectangular plate A, having a series of parallel ribs B and B, that are triangular in cross-section, the sides of each rib being respectively convex 30 and concave. Alternating with the ribs B and B are smaller angular or prismatic ribs C and C.

Having thus described my invention, what I claim is—

35 The design for a glass or light, substantially as shown and described.

In testimony that I claim the foregoing I have hereunto set my hand this 30th day of September, 1898.

WILLIAM B. JACOBS.
